FRANK C. VANDE WATER, OF NEWBURGH, NEW YORK, ASSIGNOR TO PETROLEUM LABORATORIES, INC., OF NEWBURGH, NEW YORK, A CORPORATION OF NEW YORK

PROCESS FOR CRACKING OIL

Application filed November 21, 1923, Serial No. 676,141. Renewed February 17, 1930.

My present invention relates to a method for cracking of oil in the production of gasoline and other fuel oils.

The object of the invention is to provide a process which can be put into practice with very simple and relatively inexpensive apparatus, whereby crude oil can be efficiently cracked at substantially atmospheric pressures with a minimum production of undesirable products such as carbon and diolefines.

The process generally comprises subjecting a body of crude oil in an ordinary topping still to suitable temperatures to vaporize it, preferably in the neighborhood of 400 to 450° F. After the natural gasoline and higher fractions pass off to suitable condensers, the vapors are then passed to superheating coils beneath the still which are preferably long narrow pipes in which they are subjected, without increase of pressure, to a temperature in the neighborhood of 1000 to 1300° F., depending upon the stage of the run, character of the charging stock and character of the product desired. From the super-heating coils the vapors are passed to tubes of much larger diameter, and subjected to substantially the same temperature in which the vapors, still at substantially atmospheric pressure, are subjected to a complete stabilization, but without the deposition of carbon in appreciable quantities or further the breaking down of the hydrocarbon molecules.

A preferred apparatus by which the process can be brought into practice is shown in the drawings of which,—

Figure 1 is a side elevation of the apparatus partly in section, and

Fig. 2 is a plan view of the superheating coils and stabilizing tubes.

Referring now to the embodiment illustrated, I have shown a still or tank 1 of any suitable construction which is placed over or in proximity to a fire-box or chamber 2 which may be superheated by any of the common fuels now in use, as obviously various circumstances will necessitate the use of various fuels. An aperture 3 is provided in the top of the oil tank through which the

same may be filled with the oil to be topped and cracked.

The still 1 is provided with a takeoff 4 within which is located a valve 5, which takeoff leads to a condenser 6 which may be of any of the approved types and which is merely illustrated diagrammatically.

Beneath the still and in close proximity to the fire-box 2 I provide a superheating coil 7 preferably of comparatively small diameter which is connected by means of pipe 8 to the takeoff 4 between the valve 5 and the still 1. The superheating coils are connected as by 9 to the large stabilizing tubes 10 arranged at each side of the superheating coils, and also in proximity to the fire-box 2. It will be seen that these stabilizing tubes 10 are of a much larger diameter than the superheating tubes and that therefore a certain amount of expansion takes place when the superheated vapors pass from the coil 7 to the pipe 10.

A pipe 11 connects the ends of the stabilizing tubes 10 opposite the ends at which the superheated vapors are admitted thereto, and the pipe 11 communicates with a pipe 12 which is connected on the condenser side of the valve 5 to the takeoff 4. A valve 13 is located in pipe 12 between the juncture of pipes 12 and 4 and the pipe 11.

The operation of the device is as follows:

Oil to be cracked is filled into the still 1 through the aperture 3, the valve 13 closed, valve 5 opened, and the fire started in the fire-box 2. Heat is thus applied to the body of oil within the still 1 for a sufficient length of time to remove the natural gasoline existing in the oil from the same. This vapor passes by way of pipe 4 into the condenser 6 and is condensed as gasoline. From this point it may be taken to the usual fractionators and split up into various fractions, as is the common practice, and to which no claim is made.

After the natural gasoline and the higher fractions have been thus removed, the valve 5 is closed and the valve 13 opened. Upon continued heating of the liquid in the still at a temperature in the neighborhood of 450° F., or slightly greater, depending upon the

fractions it is desired to drive off, the vapors pass through the pipe 8 into the super-heating coil 7 where they are subjected to a temperature in the neighborhood of 1000 to 1300° F. The influence causes the complete vaporization and super-heating of the vapors. From the coil 7 they pass by means of the connection 9 into the stabilizing tubes 10 where, because of the larger diameter of these latter tubes, the velocity of the vapors is considerably retarded, although the pressure is still substantially only a few pounds above atmospheric pressure. In these larger tubes a complete stabilization of the vapors is achieved without deposition of carbon or further the breaking up of the hydrocarbon molecules. The vapors then pass through the pipes 11 and 12 into the take-off pipe 4 whence they pass to the condenser 6.

It will thus be seen that under this process crude oil can be cracked efficiently without the deposition of carbon and the formation of diolefines, in an ordinary topping still beneath which the simple cracking and stabilizing tubes are disposed, thus requiring very little addition to the ordinary plant to apply this process. By carrying out the process in this manner and under very low pressures, the usual dangers encountered in the operation of high pressure plants are avoided.

I claim:

1. The process of treating liquid hydrocarbons comprising subjecting a body of oil to a vaporizing temperature, subjecting said moving vapors to a super-heating temperature in a restricted elongated space, whereby their velocity is increased, and then permitting said vapors to expand to reduce their velocity while subjected to substantially the same temperature, the entire operation taking place at substantially atmospheric pressure.

2. The process of treating liquid hydrocarbons comprising subjecting a body of oil to a vaporizing temperature in the neighborhood of 450° F., then subjecting said moving vapors to a super-heating temperature in the neighborhood of 1300° F. in a restricted elongated passage whereby their velocity is increased, and then permitting said vapors to expand to reduce their velocity while subjected to substantially the same temperature, the entire operation taking place at substantially atmospheric pressure.

In testimony whereof, I affix my signature.
FRANK C. VANDE WATER.
